UNITED STATES PATENT OFFICE

JOHN R. HOUTS, OF MCLEAN, VIRGINIA

LOG SAWING MACHINE

Application filed September 19, 1932. Serial No. 633,906.

This invention relates to log sawing machines and has for its object to provide a simple and thoroughly efficient device of this character especially designed for domestic use and by means of which logs and other timber may be conveniently sawed into predetermined lengths with very little exertion on the part of the operator.

A further object is to provide a portable machine which is light in weight and inexpensive in construction, and which may be used, with equally good results, either for sawing standing timber or for sawing logs while they are lying on the ground.

A further object is to provide novel means for guiding the saw and means coacting with the guiding means for exerting a yieldable downward pressure on the upper edge of the saw blade during the reciprocation thereof.

A further object is to provide a log saw machine including relatively stationary and movable impalement members adapted to grip opposite sides of the log and prevent turning movement thereof as the saw operates thereon.

A still further object is generally to improve this class of devices so as to increase their utility, durability and efficiency.

In the accompanying drawings forming a part of this specification:

Figure 1 is a side elevation of a log sawing machine constructed in accordance with the present invention.

Figure 2 is a top plan view thereof.

Figure 3 is a vertical sectional view taken on the Line 3-3 of Figure 1 and looking in the direction of the arrows.

Figure 4 is a detail side elevation, partly in section, showing the manner of connecting the operating lever to the saw and the construction of the locking pawls.

Figure 5 is a transverse sectional view taken on the line 5-5 of Figure 1, and looking in the direction of the arrows.

Figure 6 is a longitudinal sectional view showing the clutch lever for locking the forward impalement hooks in engagement with a log.

Figure 7 is a detail transverse sectional view showing the clutch lever in elevated

position to permit release of the forward hooks.

Similar numerals of reference indicate corresponding parts in all the figures of the drawings.

The improved device comprises a base member or frame 5 adapted to rest upon the ground when the machine is used for sawing felled timber and includes spaced side bars 6 having their forward ends inclined upwardly at 7 and adapted to extend over or rest upon the log to be sawed, indicated at 8, the rear ends of the side bars 7 being connected by a curved transverse bar 9 preferably formed integral therewith, as shown. Disposed at the rear end of the base member or frame 5 is a standard 10 preferably formed of spaced upright bars having their intermediate portions bent or coiled around the side bars 6 of the frame to form loops 11 connected by a transverse spacing bar 12 which serves to hold the side bars of the frame in proper spaced relation and imparts the desired rigidity thereto. Pivotedly mounted at 13 between the upper ends of the side bars comprising the standard is an operating lever 14, the upper end of which is extended beyond the pivot 13 to form a handle 15 while the lower end thereof is provided with a vertical slot or kerf 16 adapted to receive the heel of a saw indicated at 17. The saw 17 fits within the kerf 16 and is pivotally connected with the lower end of the operating lever at 18 so that when the handle 15 is reciprocated a corresponding reciprocatory motion will be imparted to the saw. Interposed between the upwardly inclined forward ends 7 of the frame is a vertically disposed yoke 19 having an upstanding inverted U-shaped guide 20 adapted to receive the upper edge of the saw 17 and through which said saw moves as the operating lever is reciprocated. Secured to the opposite legs of the yoke 19 are

clips or loops 21 in which the inclined portions 7 of the frame are loosely mounted so as to permit rearward movement of the yoke with respect to the supporting frame. The loops 21 are secured to the side members of the yoke by bolts or similar fastening

devices 22 and 23, the lower bolts 22 also passing through the adjacent ends of side levers 24 and serving to pivotally connect the inner ends of the side levers to the yoke, as best shown in Figures 1 and 5 of the drawings. Secured to the side bars of the standard 10 are straps 25 having their intermediate portions spaced therefrom to form guide slots 26 and through which the rear ends of the side levers 24 pass and terminate in hand grips 27. The front edges of the bars comprising the standard 10 are formed with teeth or notches 28 which coact with pawls 29 pivotally mounted at 30 on the side levers 24 and which serve to hold the yoke 19 in its forward or operative position. The pawls 29 are provided with lateral lugs 31 adapted to engage the upper edges of the side levers 24 so as to limit the downward pivotal movement thereof and hold the pawls in convenient position to be manually operated when necessary. The side members of the yoke 19 extend downwardly and are curved forwardly to form impalement members 32, the terminals of which are provided with points or spurs 32' adapted to bite into the adjacent side of the log 8 when the yoke is thrust forwardly by the action of the side levers 24. Coacting with the impalement members 32 are forward hooks or impalement members 33 having bills 34 adapted to bite into the opposite side of the log. The rear ends of the hooks 33 are curved upwardly to provide handles 35 by depressing which the hooks 33 may be disengaged from the log. Longitudinal slots 36 are formed in the intermediate portions of the hooks 33 and extending through said slots are bolts 37 which also extend through the adjacent ends of the side members 7 of the frame and through clutch levers 38 and form a pivotal connection between the parts. The clutch levers 38 are provided with bosses or projections 39 adapted to bear against the adjacent portions of the hooks 33 when said levers are swung downwardly to a horizontal position so as to wedge the hooks 33 against the side bars of the frame and thus hold the bills 34 of the hooks in engagement with the log. When the clutch levers 38 are swung to an upright position, as shown in Figure 7, the pressure of the bosses 39 will be relieved so that the hooks 33 may be readily disengaged from the log. The slots 36 permit the hooks 33 to be adjusted longitudinally, thereby to accommodate logs of different cross sectional diameters.

Pivottally mounted on the upper end of the saw guide 20 is a substantially U-shaped tension member 40, the closed end and opposite sides of which are slotted at 41 to receive a pivot pin or bolt 42 by means of which the tension member is held in position for longitudinal sliding movement on the guide 20. Journaled in the open end of the guide member 40 is a roller 43 which bears against the upper edge of the saw 17 and serves to guide said saw during its reciprocatory movement. Coil springs 44 are arranged on opposite sides of the tension device 40, one end of each spring being attached in any suitable manner to the adjacent side of the tension member in front of the pivot 42 and the other end thereof being attached to lateral arms 45 of the yoke 19, as best shown in Figure 5 of the drawings. The springs 44 tend to exert a yieldable downward pressure on the roller 43 so as to, in turn, exert a yieldable pressure on the upper edge of the saw 17 as the latter cuts through the log, the slot 41 in the tension member serving to permit longitudinal movement of said tension member and thus allow the roller 43 to accommodate itself to the saw blade as the latter saws through a log or other timber.

Slidably mounted on the curved end 9 of the frame is a loop or ring 46 to which is swiveled at 47 a corresponding loop 48 which receives one end 49 of a telescopic prop or support 50, the telescopic members of the prop or support being held in adjusted position by a set screw 51. The free end of the member 50 is retained in position on the side bar 7 of the frame by a spring clip 52 so as to support said prop 50 in inoperative position when the device is used for sawing felled timber. By removing the prop 50 from the clip 52, the latter may be readily swung downwardly so that the free end thereof may be inserted in the ground and act as a support for the rear end of the frame when the machine is used for cutting standing timber. In this connection, it is to be noted that inasmuch as the ring 46 is loosely mounted on the curved end bar 9 of the main frame, the prop or support may be suspended from the main frame at any desired point.

When the machine is to be used for cutting felled logs or other timber into predetermined lengths, the machine is positioned adjacent the log 8 and the forward impalement hooks 33 swung downwardly until the bills thereof engage one side of the log, after which the clutch levers 38 are swung downwardly to clamp the hooks 33 to the main frame and prevent accidental displacement of the bills of said hooks. The hand grips 27 are then grasped and a longitudinal pressure exerted on the side bars 24 which causes the bills 32' of the impalement members 32 to impinge the opposite side of the log from the hooks 33 and thus prevent turning movement of the log during the sawing operation. As longitudinal pressure is exerted on the handles 27, the free ends of the pawls will automatically engage the ratchet teeth and hold the impalement mem-

bers 32 securely in engagement with the log. The handle 15 of the operating member is then reciprocated so as to impart a corresponding reciprocating movement to the 5 saw blade and thus sever the log. As the saw blade cuts through the log the springs 44 will cause the roller 43 to exert a downward pressure on the upper edge of the saw blade as will be readily understood. In 10 order to release the log the clutch levers 38 are moved to an upright position and the hooks 33 swung upwardly to the dotted line position shown in Figure 1 of the drawings, after which the pawls 39 are released 15 and the side bars moved rearwardly so as to disengage the rear impalement members 32.

When cutting standing timber, the machine is placed on its side adjacent the tree 20 to be sawed and the prop 50 released from the clip 52 and swung downwardly so as to engage the ground, in which position the machine will be supported as the operator reciprocates the lever 15 to effect the saw- 25 ing operation.

A series of openings 44' are preferably formed in the lower portion of the tension device or yoke 40 in which the upper ends of the springs 44 may be fastened when said 30 yoke is adjusted longitudinally to increase or decrease the pressure exerted by the roller on the upper edge of the saw.

From the foregoing description it is thought that the construction and operation 35 of the device will be readily understood by those skilled in the art and further description thereof is deemed unnecessary.

Having thus described the invention, what I claim is:

40 1. A log sawing machine comprising a frame having upwardly deflected side bars, a standard interposed between said side bars, forward log gripping members mounted on the deflected side bars of the frame, a 45 guide yoke pivotally mounted between said deflected side bars and provided with rear log gripping members, means for forcing the rear gripping members in engagement with a log, a saw mounted for reciprocation 50 in the guide yoke, an operating lever pivotally mounted on the standard and operatively connected with the saw, and means carried by the guide yoke for exerting a yieldable downward pressure on the upper 55 edge of the saw.

2. A log sawing machine comprising a frame, a standard connected with the frame, a guide yoke slidably mounted on the frame and provided with impalement members 60 adapted to grip one side of a log, impalement hooks pivotally mounted on the frame and adapted to engage the other side of the log, clutch levers coacting with the impalement hooks and provided with bosses 65 adapted to engage the frame for holding

the hooks against pivotal movement, an operating lever pivotally mounted on the standard, a saw operating in the guide yoke and pivotally connected with the operating lever, and a tension device carried by the 70 guide yoke and adapted to bear against the upper edge of the saw.

3. In a log sawing machine, a supporting frame, a guide yoke slidably mounted on the frame and provided with impalement members, hooks mounted on the frame and coacting with the impalement members to grip a log, an operating lever, a saw mounted for reciprocation in the guide yoke and pivotally connected with the operating 75 lever, a tension member mounted on the guide yoke and adapted to engage the upper edge of the saw, and springs forming a yieldable connection between the guide yoke 80 and said tension member.

4. In a log sawing machine, a frame, a yoke having impalement members adapted to grip one side of a log and provided with an upstanding guide loop, log gripping 90 hooks mounted on the frame and coacting with the impalement members, a saw mounted for reciprocation in the guide loop, an operating lever pivotally connected with the saw, a longitudinally slotted U-shaped 95 frame pivotally mounted on the guide loop, a roller mounted in the open end of the U-shaped frame and adapted to bear against the upper edge of the saw, and yieldable means forming a connection between the 100 yoke and said frame.

5. In a log sawing machine, a frame, a standard rising from the frame, strap irons secured to the standard and spaced therefrom to form guides, a yoke slidably mounted on the frame and provided with impalement members, hooks pivotally mounted on the frame and coacting with said impalement members, side bars connected with the yoke and having their rear ends extended 105 through the guides, ratchet teeth formed on the standard, pawls pivotally mounted on the side bars and coacting with the ratchet teeth, a saw blade mounted for reciprocation in the yoke, and an operating lever pivotally mounted on the standard and having its lower end pivotally connected 110 with the saw blade.

6. In a log sawing machine, a supporting frame, a standard secured to the frame, a yoke slidably mounted on the frame and provided with a guide loop, said yoke being formed with terminal impalement members, slotted hooks coacting with the impalement members and operatively mounted on 120 the frame, clutch levers having bosses adapted to bear against the frame for holding the hooks in engagement with a log, a saw mounted for reciprocation in the guide loop, an operating lever pivotally mounted on the 125 standard and pivotally connected with the 130

saw, and means for holding the impalement members in engagement with the log.

7. In a log sawing machine, a substantially U-shaped supporting frame having side bars the forward ends of which are inclined upwardly, a standard interposed between the side bars at the rear end of the frame, a yoke interposed between and slidably mounted on the forwardly inclined portions of the side bars of the frame and having its upper end provided with a reduced vertically disposed guide and its lower end provided with impalement members, hooks pivotally mounted on the inclined portions of the frame and having their intermediate portions provided with slots and their inner ends extended upwardly to form handles, clutch levers having bosses thereon adapted to engage the frame to hold the hooks in engagement with a log, a saw mounted for reciprocation in the guide, an operating lever pivotally mounted on the standard and pivotally connected with the rear end of the saw, and a tension device pivotally mounted on the upper end of the guide and including a roller adapted to yieldably engage the upper edge of the saw.

8. In a log sawing machine, a supporting frame including upwardly inclined side bars, a yoke interposed between the inclined side bars and provided at its upper end with a reduced extension forming a guide loop, impalement members carried by the lower ends of the yoke, clips secured to the yoke and encircling the inclined side bars, hooks pivotally mounted on the inclined side bars and coacting with the impalement members, means for holding the hooks in engagement with the work, means for moving the impalement members into and out of engagement with a log, a standard carried by the frame, a saw mounted for reciprocation in the guide loop, an operating lever pivotally mounted on the standard and pivotally connected with the saw, and a longitudinally slotted tension device pivotally mounted on the upper end of the guide loop and yieldably engaging the upper edge of the saw.

9. In a log sawing machine, the combination with a frame, a yoke carried by the frame and provided with impalement members, hooks mounted on the frame and coacting with the impalement members to grip a log, means for locking the hooks in engagement with the log, means for moving the impalement members into and out of engagement with the log, a saw mounted for reciprocation in the yoke, an operating lever connected with the saw, and a tension device carried by the yoke and adapted to engage the upper edge of said saw.

10. In a log sawing machine, the combination with a frame, a yoke slidably mounted for swinging movement on the frame and provided with impalement members, hooks

pivotaly mounted on the frame and coacting with the impalement members to grip a log, means for holding the hooks in engagement with said log, a saw mounted for reciprocation in the yoke, an operating lever pivotally connected with the saw, means operatively connected with the yoke for moving the impalement members into and out of engagement with the log, means for locking the impalement members in operative position, and a longitudinally adjustable tension device pivotally mounted on the yoke and normally exerting a yieldable pressure on the upper edge of the saw.

11. In a log sawing machine, a substantially U-shaped frame having its closed end transversely curved, a saw mounted for reciprocation on the frame, coacting gripping members adapted to engage a log, an operating lever connected with the saw, a loop slidably mounted on the curved end of the frame, a support pivotally mounted on the loop, and means carried by the frame and adapted to engage the support for holding the support in inactive position.

12. In a log sawing machine, the combination with a frame including upwardly inclined side bars, a yoke interposed between the side bars and slidably connected therewith, said yoke being provided with terminal impalement members, hooks having their intermediate portions slotted and their inner ends curved upwardly, said hooks co-operating with the impalement members to grip a log, clutch levers having bosses adapted to engage the inclined bars of the frame for holding the hooks in engagement with the log, bolts passing through the inclined portions of the frame, and slots in the hooks and said clutch levers and forming a pivotal connection between the same, a saw mounted for reciprocation in the yoke, an operating lever pivotally connected with the rear end of the saw, means for moving the impalement members into and out of engagement with the log, and means for holding said impalement members in operative position.

In testimony whereof I affix my signature.
JOHN R. HOUTS. [L. S.]
